CLAIM

The ornamental design for a hair straightener, as shown and
described.

DESCRIPTION

FIG. 1 is a perspective view showing the first embodiment
of a hair straightener;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof;
FIG. 7 is a bottom plan view thereof;
FIG. 8 is a perspective view showing the second embodiment
of a hair straightener;
FIG. 9 is a front elevational view thereof;
FIG. 10 is a rear elevational view thereof;
FIG. 11 is a right side elevational view thereof;
FIG. 12 is a left side elevational view thereof;
FIG. 13 is a top plan view thereof; and,
FIG. 14 is a bottom plan view thereof.

The broken lines in the figures depict portions of the hair
straightener that form no part of the claimed design.
